United States Patent Office

Des. 214,866
Patented Aug. 12, 1969

214,866

CARTON STAPLING MACHINE OR SIMILAR ARTICLE

Jack Garfinkel, Bayside, N.Y., assignor to Swingline
Inc., Long Island City, N.Y., a corporation of New York

Filed Oct. 14, 1968, Ser. No. 13,968

Term of patent 14 years

Int. Cl. D8—02

U.S. Cl. D8—49

FIG. 1

Des. 214,866

PAGE 2

FIG. 2

Des. 214,866

FIG. 3

FIG. 4

FIG. 1 is a side elevational view of a carton stapling machine showing my new design.

FIG. 2 is a top plan view thereof.

FIG. 3 is a front elevational view thereof.

FIG. 4 is a rear elevational view thereof.

The side opposite that shown in FIG. 1 is substantially a mirror image thereof.

I claim:

The ornamental design for a carton stapling machine or similar article, as shown and described.
